US00D994988S

(12) **United States Design Patent** (10) **Patent No.:** **US D994,988 S**
(45) **Date of Patent:** **** Aug. 8, 2023**

(54) **SPORTS MASK**

(71) Applicant: **Do Soon Kim**, Seoul (KR)

(72) Inventor: **Do Soon Kim**, Seoul (KR)

(73) Assignee: **KUMKANG ENS CO., LTD.**, Seoul (KR)

(**) Term: **15 Years**

(21) Appl. No.: **29/738,360**

(22) Filed: **Jun. 17, 2020**

(30) **Foreign Application Priority Data**

Dec. 18, 2019 (KR) 30-2019-0061554

(51) **LOC (14) Cl.** **29-02**

(52) **U.S. Cl.**

USPC **D29/108**

(58) **Field of Classification Search**

USPC D29/108, 111, 122; D28/4, 7, 9

CPC ... F41H 1/08; A41D 13/1107; A41D 13/1161;

A41D 13/1184; A42B 3/18

(57) **CLAIM**

The ornamental design for a sports mask, as shown and described.

DESCRIPTION

FIG. 1 is a perspective view of the sports mask showing my new design;

FIG. 2 is a front view thereof;

FIG. 3 is a rear view thereof;

FIG. 4 is a top plan view thereof;

FIG. 5 is a bottom plan view thereof;

FIG. 6 is a left side view thereof; and,

FIG. 7 is a right side view thereof.

The broken lines of FIGS. 1-7 illustrate portions of the sports mask that form no part of the claimed design.

1 Claim, 7 Drawing Sheets
